Patented Nov. 30, 1965

203,066

DISPENSER FOR POWDERED MATERIAL

Sidney Sawyer, 18 Cromwell Drive, Morristown, N.J.,
and William J. Corcoran, 5 Smithfield Lane, Florham
Park, N.J.

Filed Nov. 25, 1964, Ser. No. 82,773

Term of patent 14 years

(Cl. D52—2)

FIG.1

FIG.3

FIG.2

FIG. 1 is a perspective view of the dispenser for powdered material embodying our new design,
FIG. 2 is a front elevational view thereof,
FIG. 3 is a right-side elevational view thereof,
FIG. 4 is a back elevational view thereof, and
FIG. 5 is a left-side elevational view thereof.
The broken line portion shown in FIG. 1 of the drawings is for illustrative purposes only.

We claim:

The ornamental design for a dispenser for powdered material, as shown and described.
